UNITED STATES PATENT OFFICE.

ROBERT C. WAGNER, OF TOLEDO, OHIO.

MOVING-PICTURE APPARATUS.

No. 811,341.

Specification of Letters Patent.

Patented Jan. 30, 1906.

Application filed December 3, 1904. Serial No. 235,339.

To all whom it may concern:

Be it known that I, ROBERT C. WAGNER, a citizen of the United States of America, residing at Toledo, in the county of Lucas and State of Ohio, have invented certain new and useful Improvements in Moving-Picture Apparatus, of which the following is a specification, reference being had therein to the accompanying drawings.

This invention relates to certain new and useful improvements in moving-picture apparatus, and relates in particular to that class of moving-picture apparatus known as "mutoscopes," and the object of this invention is to provide a mutoscope wherein stereoscopic effects can be produced, so that the moving pictures will have in addition to the effect of an animated scene or picture which is produced in the ordinary mutoscope the well-known and beautiful appearance of relief and aerial perspective which is seen in the stereoscope.

Another object of this invention is to provide a mutoscope wherein a plurality of cylinders each provided with photographic or other reproductions are arranged so that the pictures on the several cylinders may be successively viewed.

A still further object of this invention is to provide novel means in a mutoscope for casting upon the pictures to be viewed rays of light of various colors, this feature of the invention being particularly applicable when the pictures to be viewed are of certain classes, such as rainbow, butterfly, serpentine, and other dances.

A still further object of this invention is to provide novel coin-controlled and electrically-actuated mechanism for successively bringing into the range of vision the several sets of pictures carried by the several cylinders above-mentioned.

The invention has for its object in addition to the objects mentioned above the provision of novel mechanism for effecting the several operations of the device, which mechanism will be hereinafter fully described; and the invention consists in the novel means for accomplishing the several objects defined and others that will be hereinafter developed and set forth.

In the accompanying drawings, illustrating this invention, similar letters and numerals are used in the several views to designate corresponding parts.

In the drawings, Figure 1 is a vertical

transverse sectional view of the complete apparatus constructed according to my invention. Fig. 2 is a detail elevation, partly in section, of one of the picture-carrying cylinders, showing the mechanism by means of which the cylinders are revolved and stopped when they have made a complete revolution. Fig. 3 is a side elevation of the mechanism for revolving the cylinders shown in Fig. 2. Fig. 4 is a vertical longitudinal sectional view through the casing of the apparatus on the line 4-4 of Fig. 1 looking toward the front of the casing. Fig. 5 is an enlarged vertical sectional view of a portion of the casing of the apparatus, showing in detail portions of the coin-controlled and electrically-actuated mechanism for successively bringing the several cylinders into view and turning the cylinders. Fig. 6 is a fragmentary view, partly in section, of the mechanism for moving the cylinders successively into the line of vision of a person using the machine; and Fig. 7 is an end view of one of the cylinders, showing the manner of attaching the picture-mountings thereto.

Referring to Fig. 1 of the drawings, it will be seen that the apparatus is mounted in a substantially cylindrical case B, which is mounted on a hollow pedestal C and is provided with a hinged door A, by means of which access may be had to the case. Within the case B are mounted three sets of photographic or other reproductions of moving pictures, the three sets being lettered, respectively, A', A'', and A''. The pictures are mounted upon flexible mountings, such as cardboard, and each set of pictures, it is to be understood, are stereoscopic pictures—that is, each card contains two similar views made in the manner of the well-known stereoscopic photographs—and these pictures are viewed through a stereoscope S, mounted at a suitable and convenient point in the case B. In the drawings I have shown only a portion of each set of picture-mountings, so as to avoid obscuring the view of certain parts of the mechanism; but it is to be understood that each set of pictures entirely surrounds the shaft on which it is mounted, the arrangement being the same as that in the ordinary mutoscope, with the exception that the picture-mountings are secured in place in a novel manner, which will be hereinafter described. The several sets of pictures are mounted upon hubs or cylinders F', F'', and F''', respectively, and these hubs have at their ends stub-shafts

8 9, which are journaled in the arms of three-
5 armed spiders D, while the spiders are mounted
on a shaft E, which is journaled in the sides of
the casing. Arms 5 5 extend out from one side
of the legs of the spiders at each side of each
10 of the picture-carrying hubs, and these arms
carry cross-bars 6, upon which are pivotally
mounted spring-fingers H, that serve to hold
the edges of the picture-mountings so that
15 as the hubs are turned the pictures will be
successively exposed to view in the well-
known manner employed in the ordinary
mutoscopes.

15 A worm-wheel P, which is provided with
an integral sleeve p, is mounted on the shaft
E outside the spider on one end of the shaft,
and a spiral spring 1 surrounds this sleeve
and is attached at 2 to the worm-wheel P and
20 is attached at 3 to the hub of the spider D.
The worm-wheel P is loosely mounted on the
shaft E and is held against longitudinal move-
ment by a collar e, which is fixed in position
on the shaft by a set-screw.

25 A horizontal shaft L is journaled in a frame
J, secured upon the inside of the case B, and this
shaft carries on its inner end a worm O,
that meshes with the worm-wheel P, so that
when this shaft is turned the spiders D will be
30 revolved on the shaft E, so as to successively
bring the several sets of pictures within the
line of vision through a stereoscope S. The
shaft L has a bearing in a sleeve M, which is
journaled in the case B, and the sleeve M has
35 affixed to its outer end outside the case a han-
dle T, by means of which the sleeve M may be
revolved. A cup-shaped friction clutch mem-
ber 23 is formed integral with the sleeve M,
and a friction-plate 24 is formed integral with
40 a sleeve 24', that is mounted on the shaft L,
and the plate 24 is brought into contact with
the clutch member 23 when the shaft L is to
be revolved. The sleeve 24' is formed with a
slightly-oblong opening 25', in which works a
45 pin 25, that passes transversely through the
shaft L, the oblong opening permitting of a
limited movement of the sleeve 24' on the
shaft L and the pin causing the shaft to be
turned when the friction clutch-plate 24 is
50 turned. A spring 28 is secured at one end to
the shaft L and at the other end to the sleeve
24', and this spring serves to normally draw
the plate 24 away from the clutch member
23. The sleeve 24' is formed with a periph-
55 eral groove 26, which is embraced by the bi-
furcated arms 27 of a bell-crank lever 29,
that is pivotally mounted on a shaft 29' and
pivotally connected to the cores 30 of solen-
oid 31, that is mounted in fixed position on
60 suitable brackets 32, secured to the case B.

65 In Fig. 1 of the drawings it will be observed
that one of the sets of pictures is in such pos-
ition that one of the pictures thereon (lettered
Y) is in the line of vision through the stereo-
scope S, and this picture and each picture
65 which is successively exposed to sight by the

revolution of the hub F' is illuminated by the
light from an incandescent electric lamp W,
which is mounted in a cylindrical casing U,
formed integral with the main case B and hav-
ing an opening at one point within the case B. 70
The lamp W is surrounded by a cylinder of
glass or other transparent material V, and this
cylinder is differently colored for portions of
its periphery, being provided with any desired
75 number of colored sections, so that as the cyl-
inder is revolved the color of the light thrown
on the pictures exposed to view will change,
and the cylinder is revolved during the revo-
lution of the picture-carrying hub by means
80 of a belt X', running to a pulley L' of the shaft L.

The coin-controlled mechanism by means
of which the operation of the apparatus is
governed will be best understood by referring
to Fig. 5 of the drawings, and reference being
now had to this figure it will be seen that a
85 coin-chute 32 is fixed in the case B, this coin-
chute being straight for a portion of its length
and curved downwardly for the remainder of
its length. The coin-chute (designated 32) is
90 provided with a slot 33 in its side, said slot
being provided for the purpose of allowing a
coin of wrong denomination to drop out of
the side of the chute before operating the elec-
trical appliances heretofore described. The
95 curved end of the chute is hinged to the
straight portion of the same at 34, and a light
spring 34a is fixed on the side of the chute, so
as to normally maintain the curved portion
100 of the same in alignment with the straight
portion thereof. A bolt 35 is supported in a
fixed arm 36 and impelled in a direction away
from the chute by a spiral spring 36a. Each
105 of the arms of the spider on one side of the
picture-carrying hubs is formed with an abut-
ment Q, which at a certain position of parts
bears against the bolt 35, so as to push the
110 same toward the curved portion of the coin-
chute, and the bolt 35 is beveled on one edge,
so that when it is impelled forward by the
abutment Q it will press against the side of
115 the coin-chute and swing the curved portion
thereof slightly to one side. An arm 38 is
swiveled on a shaft 39, and this arm projects
under the curved end of the coin-chute and
120 serves to receive a coin and hold the same in
position during the time a set of pictures is
being exhibited. A pin 37 projects laterally
from an arm on the lower end of the curved
125 portion of the coin-chute, and when the said
curved end of the coin-chute is moved to one
side by the bolt 35 this pin serves to sustain
the arm 38 in proper position. A spring con-
tact-plate 40 is mounted in a binding-post 42
just above the outer end of the arm 38, and
this spring contact-plate carries a contact-
point that makes contact with a contact-
point carried by a fixed bar 41 when the arm
38 is depressed by the weight of the coin. A
130 wire marked + is connected to the binding-

post 42, and the wire marked — is connected to the bar 41, and these wires constitute a portion of the electric circuit which passes through the incandescent lamp W and through the solenoid 31, it being understood, of course, that current is supplied to this circuit from a suitable source of electrical energy.

Referring to Figs. 2 and 3, which show in detail the mechanism for revolving the picture-carrying hubs, 10 designates a short shaft which is journaled in the frame J, and upon this shaft is mounted a worm-wheel I, that meshes with a worm K, fixed on the shaft L. The worm-wheel I has a hub I' on its inner side, and this hub is formed with a diametrical slot I², into which the squared end 8' of the shaft 8 fits when the spider has been revolved so as to bring the shaft 8 into alignment with the shaft 10 of the worm-wheel I. The frame J is formed with a lateral extension J', and in this extension is pivotally mounted a pivoted trigger 15, which is normally pressed outwardly by a spring 16. The trigger 15 normally stands in such position that its upper end will lie along the abutment Q on that end of the arm of the spider which carries the set of pictures about to be exposed to view. A pin 18 is carried by the worm-wheel I near the rim thereof, and this pin as the worm-wheel is revolved contacts with the lower end of the trigger 15 and throws the upper end of the trigger from beneath the abutment Q when the worm-wheel has made a complete revolution and all the pictures thereof have been exposed to view.

Referring to Fig. 7 of the drawings, wherein I have illustrated the means for securing the picture-mountings to the hubs, F' designates one of the hubs, and in this hub, at each end thereof, are mounted the radially-disposed spring-arms 22, and these spring-arms carry metallic rings 21, that are radially slitted on their inner sides to receive the picture-mountings 11, these mountings being pushed into the radial slits in the rings at each end of the hub, so that the mountings project radially all around the hub. I have shown in this figure but a limited number of the picture-mountings, some of them being shown as being straight and some of them bent to the position they assume while they are being restrained by the spring-finger H in the position shown in Fig. 1. The result accomplished by attaching the picture-mountings in this manner is that a short card can be used and it dispenses with the necessity of directly attaching the inner edges of the mountings to the hub. The spring-sustained rings 21 give added resiliency to the picture-mountings and cause them when released to pass quickly out of the line of sight.

The operation of my apparatus is as follows: A coin being dropped in the coin-chute 32 falls upon the arm 38 and depresses the same, causing the spring-tongue 40 to be

pressed upwardly and bringing it into contact with the contact-point carried by the fixed arm 41. A circuit is thus established through the lamp W and the solenoid 31, and the lamp is lighted, and simultaneously with the lighting of the lamp the solenoid-core 30 is drawn into the solenoid and the clutch-plate 24 is brought into contact with the clutch member 23. The handle T is now turned and the shaft L revolved. The worm-wheels I and P will be turned by the worms K and O; but the worm O and worm-wheel P are so constructed relatively to the worm K and worm-wheel I that the worm-wheel P will be turned but a portion of a revolution during the time the worm-wheel I is making a complete revolution. The turning of the worm-wheel I causes the pictures on the hub F' to be successively exposed to view, and at the same time the revolution of the transparent cylinder V will change the light which is being cast upon the pictures from the lamp W. As the worm-wheel P revolves the spring 1 will be wound up, and eventually when the spider is released the resiliency of this spring will cause the spider to revolve on its shaft and bring another set of pictures into position to be viewed through the stereoscope S. When the worm-wheel I has made a complete revolution, it is stopped at the position from which it is started by means of a spring-pin 19, that springs into a socket Z in the spider-arm, and at this moment pin 18 contacts with the lower end of the trigger 15 and throws the trigger from under the abutment Q on the end of the spider, and the resiliency of the spring 1 causes the spider to revolve and bring another set of pictures into position to be viewed through the stereoscope, the spider as it turns being stopped after it has made a third of a revolution by the contact of the abutment Q on the next succeeding arm of the spider with the trigger 15, which by this time has resumed its normal position below such abutment. As the spider revolves in the manner above described the abutment Q of the spider, which is coming forward and downward into the horizontal position just before it reaches the trigger 15, strikes the outer end of the bolt 35 and pushes the same toward the hinged end of the coin-chute, this movement of the bolt having the effect of pushing the hinged end of the coin-chute slightly to one side and permitting the coin therein to drop into a suitable receptacle, (not shown and arranged at a suitable point within the case B.) The dropping of the coin permits the arm 38 to resume its normal position and break contact between the contact-plate 40 and the fixed contact in the arm 41. The electrical circuit being thus broken, the solenoid 31 will be deenergized, and the spring 28 will throw the clutch-plate 24 away from the clutch member 23, and simultaneously the light of the lamp W will be extinguished.

By the construction of the hub and its connections I am enabled to readily replace any set of pictures with another set by merely removing the shafts 8 and 9 at one end of the hub and lifting the hub out of the spider and replacing it with a hub provided with a different set of pictures.

Having described my invention, what I claim, and desire to secure by Letters Patent, is—

1. The combination in a mutoscope, of a rotary hub, a series of pictures mounted on said hub, means for rotating the hub, a stationary light arranged to illuminate the pictures carried by the hub, a party-colored cylinder surrounding said light, and means whereby said cylinder will be revolved simultaneously with the revolving of the hub.
2. In a mutoscope, the combination of a case, a spider mounted to revolve in said case, a plurality of hubs journaled in said spider, mutoscopic pictures mounted on said hubs, means for revolving the spider so as to bring the hubs successively to a predetermined point, and means for revolving each hub after it has reached said predetermined point.
3. In a mutoscope, the combination of a case, spiders revolvably mounted in said case, a plurality of hubs mounted in said spiders, means for revolving the spiders to bring the hubs successively to a predetermined position, and within the range of vision, means for stopping the revolution of the spiders when one of said hubs has reached such predetermined position, means for revolving the hub which has reached the aforesaid position, means for automatically releasing the spiders when the hub has made a complete revolution, means for automatically stopping the next-succeeding hub at the position occupied by the hub first thrown into action.
4. In a mutoscope, the combination of a rotary spider, a plurality of mutoscopic hubs mounted on said spider and carrying muto-

scopic pictures, a manually-operated shaft, a clutch member carried by said shaft, a shaft operably connected to and adapted to turn said spider, a clutch member carried by the last-mentioned shaft, means carried by said shaft for turning one of the hubs, a solenoid having a core connected to the last-named clutch member, electrical circuits including said solenoid, means for completing said circuit and thereby energizing the solenoid whereby said clutch members will be brought into engagement with one another.

5. In a mutoscope, the combination of a plurality of mutoscopic hubs each furnished with a set of pictures, means for successively bringing the pictures on each hub into sight, and means for revolving each hub when brought into sight so as to successively expose the pictures thereon to view.

6. In a moving-picture apparatus, the combination of a plurality of sets of moving pictures, means for successively bringing each set of pictures into a position to be viewed, and means for operating each set of pictures so as to produce a moving-picture effect.

7. In a moving-picture apparatus, the combination of a plurality of sets of moving pictures, means for successively bringing each set into view, means for illuminating the pictures when brought into view, and means for changing the character of the illumination during the time the pictures are being viewed.

8. In a mutoscope, the combination with a hub of springs projecting from said hub, radially-slotted rings carried by said springs and adapted to receive the edges of picture-mountings.

In testimony whereof I affix my signature in the presence of two witnesses.

ROBERT C. WAGNER.

Witnesses:

L. SPITZIG,
E. J. KESLER.
